INCANDESCENT LIGHT FOR PROJECTION APPARATUS.

1,221,418.

Specification of Letters Patent. Patented Apr. 3, 1917.

Application filed October 17, 1912. Serial No. 726,204.

To all whom it may concern:

Be it known that I, EMERSON L. CLARK, a citizen of the United States, and a resident of Lakewood, in the county Cuyahoga, in 5 the State of Ohio, have invented new and useful Improvements in Incandescent Light for Projection Apparatus, of which the following is a clear and exact description.

My invention relates to lamps for projecting images on screens. The usual light now in use for projection work, particularly moving picture apparatus, is the electric arc lamp. In order to use an electric arc to project the moving picture, for instance, on 10 a screen it is necessary to place the film at a certain distance away from the arc and to throw the light on it by means of a condensing lens. It is impractical to place the film close to the arc without any intervening condenser, as the light from the arc is so irregular that the screen would not be equally 15 lighted.

One of the objects of my invention is to obtain an electric light source that is uniformly 20 distributed over the light emitting area.

Another object is to use in combination with the source of uniformly distributed light a special projecting lens so that it can 25 be placed closer to the moving picture film or other like part, and still project the desired size of image on the screen.

Another object is to construct a lamp having an incandescent filament and arranged 30 in such a manner that ample light can be furnished for projection work.

Other objects will appear in the appended 35 description.

In the drawings:

40 Figure 1 is a diagrammatic view of my improved incandescent projecting lamp shown in position for projecting the picture on a screen, the parts being shown in a more or less diagrammatic relation.

45 Fig. 2 is a representation of another form of my invention shown in position for projecting the picture on a screen by means of a special projecting lens.

50 Referring to Fig. 1, 1 represents a globular part made of glass or any other material having a highly polished reflecting surface 2 on the interior. The drawing shows the lamp as composed somewhat in the same manner as the usual incandescent lamp hav-

ing a central rod 3 sealed into the glass bulb 55 and carrying incandescent wires 4, here shown as metallic filaments composed preferably of tungsten. It is not absolutely necessary that the disk 6 be separate from the bulb. If desired a sufficient area of the 60 interior may be coated with some material to prevent its being coated with silver when the bulb is being silvered and then removing the coat, or the entire bulb may be silvered and part of it removed for the window. The 65 bulb may have the usual socket 5. At one side of the glass bulb a disk 6 pervious to light and preferably of glass is sealed into an opening previously made in the bulb and serves for what I call the window. How- 70 ever, before the bulb is sealed and preferably before the disk 6 is placed therein, the interior is highly polished and preferably sil- 75 vered so as to give a highly reflecting surface. The idea is to get as efficient reflecting 80 surface as possible, hence any materials may be used such as silver, nickel, speculum metal, etc., to furnish it. Silver is the most efficient now known and therefore I prefer to use this as the reflecting surface. After 85 the filament has been placed in the bulb and the disk 6 sealed in, the air is exhausted from the interior and the tip 7 is sealed. With the exception of the silvered interior of the bulb and the window 6, the construc- 90 tion of this lamp is substantially the same as the ordinary incandescent lamp and further description of its mode of construction is not necessary.

With a source of light surrounded by a 90 reflecting surface and having a certain area of the surface composed of a medium per- 95 vious to light, all of the light emitted from the source must eventually proceed through such area provided the efficiency of the reflecting surface is 100% and the surface is not perfectly smooth. That is, if all the light is reflected back and forth from the reflecting surface and none of it is absorbed, it must all be emitted through the light per- 100 vious area. However, a reflecting surface of approximately 90% efficiency is as high as is at present obtainable, so that with a lamp constructed as described the entire light emitted from the source will not pass out 105 through the window, but a certain amount will be absorbed.

The concentrating effect produced by my

arrangement may be approximately computed as follows: Let I be the mean spherical intensity of the extended source within the reflecting inclosure; let R be the reflecting coefficient of the reflecting inclosure; let P be the per cent. area which is uncoated with reflecting material; let r be the radius of the inclosure (assumed spherical), then the intensity of illumination produced at the 10 window 6 is:

$$\frac{I}{r^2} \times \frac{100}{100 - (R - P)}.$$

If polished silver is used and a window of 15 1% area provided, there will be an intensification of

$$\frac{100}{100 - (90 - 1)} = 9$$

20 times the intensity which would be produced were all the light concentrated in a point at the center and with no reflecting inclosure. Since this light comes largely from multiple reflections, the light flux within the 25 inclosure is substantially uniform in all directions, hence the distribution of intensity about a small light-pervious area will follow approximately the cosine law. It will thus be seen that my invention provides for 30 getting a light source combining the qualities of constant form, fixed position, uniform illumination, high intensity and simplicity in a high degree, thus making it suitable for projection purposes.

35 The preceding law applies specifically to diffused reflection but is substantially correct for what is commonly termed specular reflection, as it is impossible to obtain an absolutely smooth reflecting surface. Inasmuch 40 as the reflecting surface on the interior of the bulb is made up of a myriad of minute discontinuous surfaces, substantially all rays proceeding from the light source will eventually emerge through the window and the 45 above law will hold.

Since the light proceeding through this disk is of uniform intensity, the aperture plate 8 may be placed near or against the window 6 so that the film or plate 9 can be placed very near to the source of light, or the aperture plate may be omitted entirely. The usual projection lens 10 can then be used to throw the picture on the screen 11.

The size of the projection on the screen 11 50 is to the size of the picture on the film 9 as the distance b is to the distance a . In moving picture apparatus the distance a is usually from 6 to 10 inches, hence with a lens 10 as shown in Fig. 1 it will not be possible 55 to place it any nearer than this to the film or plate 9 because the projection on the screen 11 would then be entirely too large. However, in connection with Fig. 2 I have shown a special projection lens which can be placed 60 close to the film so that there is a greater per-

cent. of the light thrown upon the screen. Further description of this special projecting lens will be given later.

It is, of course, preferable to have the reflecting surface on the interior of the glass bulb, but such surface may be placed on the exterior. With this arrangement, however, there would be a much greater absorption of light so that the efficiency would be diminished.

75 Since the greater part of the energy from the electric lamp is transformed into heat, the surrounding medium will become very hot unless means are provided for cooling it down. In Fig. 2 I have shown the source of light constructed so that it can be properly cooled. In this figure the globe consists of two hemi-spherical parts 12 and 13 having the water jackets 14 and 15 therein. These hemi-spherical parts can be cast of any metal 80 and the method by which such castings are made is well known in the art so that further description need not be given. The two parts 12 and 13 have their interior surface 16 highly polished and silvered or coated with any other highly reflecting material. The incandescent support 17 is cemented or otherwise fastened to the part 12 and the terminals 18 and 19 are properly sealed by the parts 20 and 21 which must be of insulating 85 material or else the terminals must be otherwise insulated from the parts 20, 21 in order to prevent a short circuit. The disk 22 which serves as the window is cemented or otherwise secured in the hemi-spherical part 13 as shown and the two parts 12 and 13 are securely fastened together to make an air-tight joint. The fluid cooling of the metallic hemispherical part prevents the temperature of the entire inclosure from increasing to any considerable extent. Since the temperature of the glass, which has the lower coefficient of expansion, will be greater than the temperature of the fluid cooled metal, the difference in the coefficients of expansion of the 90 glass and the metallic part will thus be compensated. Various other schemes however, may also be used to secure the desired result. They may be soldered or joined in any manner, but I have shown them as having the flanges 23, 24 fastened together by means of screws 25. A gasket may be used between the flanges if desired.

100 After the two hemi-spherical parts have been fastened together as described the air is exhausted from the interior through a tube 26 and the latter is sealed. If desired a valve could be placed in the tube 26, but it is 105 preferably sealed by heating it until it is plastic enough to weld together. Another way to seal the tube is to coat it on the inside with a thick coat of solder or brazing material before it is placed in the part 12. Then when the air is exhausted the tube 26 110 can be heated until it is plastic enough to be 115 120 125 130 135 140 145 150 155 160 165 170 175 180

pressed together, and if the lamp is held so that the tube extends downward the solder will soften and flow into the constricted end and seal it.

5 Water may be circulated through the cavities 14 and 15 by means of pipes 27, thus preventing the lamp from becoming unduly heated.

In order to be able to use the projecting 10 lens close to the film or plate 9, a special lens arrangement is used. This consists of a converging lens 28 and a diverging lens 29 spaced apart so as to have their nodal point *c* between the lens and the screen 11. By selecting the right curvature for the two lenses 15 and spacing them apart the proper distance, the nodal point may be spaced the same distance from the screen as the nodal point *c* of Fig. 1 and yet have the projecting lens 20 placed close to the film 9. The two lenses 28 and 29 may be appropriately secured in a casing 30.

In Fig. 1 as well as in Fig. 2 the filament 25 supporting means may be silvered to increase the reflecting efficiency.

With my invention it will be seen that sufficient light is obtained from an incandescent source to use it for projection purposes by reason of the peculiar construction of the 30 silvered surface and by placing the film and the projection lens close up to the source of light. The advantages of this arrangement over the arc light projection apparatus will be obvious. After the lamp is placed in position no further attention need be paid to it until it is burned out. Thus the operating 35 expenses are reduced. The light obtained from this incandescent source has a uniform intensity and this is admirably suited for 40 projection purposes.

My invention is not to be limited to the use of a reflecting surface around the source of light, as I believe I am the first to use an

extended source of light of substantially unvarying intensity throughout its area, and of 45 substantially the same size as the aperture plate of the picture on the film. This enables me to place the film or plate immediately adjacent the source of light and within what I may call the limits of the focal plane 50 conjugate to the screen without projecting any variations due to the source of light. There is a limiting distance back of the film that an arc light or other light of non-uniform intensity can be placed and not project a noticeable image of itself on the screen. If those lights of non-uniform intensity are placed between this limit and the film they will be projected on the screen in a more 55 or less distinct manner depending upon their nearness to the film. The window in my device having a light of uniform intensity throughout its entire area, can be placed near the film and within the said limit, as its image is a uniform sheet of light, and hence 60 it produces no unevenness of the projected 65 image of the picture.

Having described my invention what I claim is:

1. In an incandescent light, a light emitting filament and a bulb surrounding the filament, the greater part of said bulb having a highly reflecting surface and the remaining part adapted to serve as a window. 70

2. In an incandescent light, a light emitting filament and a bulb surrounding the filament the greater part of the bulb having a highly reflecting surface on its interior, the remaining part of the bulb serving as a window for the emission of reflected light. 75 80

In testimony whereof I have hereunto signed my name.

EMERSON L. CLARK.
